Fig. 4

The band that encircles the inside of the cuff fold is stippled to represent a color contrast.

This application is a division of my application Serial No. D. 82,559, filed November 12, 1964 and now abandoned.

I claim:

The ornamental design for a shirt cuff, substantially as shown and described.
